POULTRY PACKING TABLE

Ray V. Mathews, Ottumwa, Iowa, assignor to
Swift & Company, Chicago, Ill., a corporation
of Illinois

Application December 7, 1948, Serial No. 63,999

2 Claims. (Cl. 226—129)

1

This invention relates to packaging equipment, and more particularly to an arrangement to facilitate the loading of dressed poultry products into a shipping case.

It is an object of this invention to provide an improved working table for the loading of poultry products for shipment in the trade.

It is another object of this invention to provide an improved packing table to facilitate the lining of a wire-bound box with a paper liner and the loading of the box with poultry product.

It is another object of this invention to provide a working table for use during the operation of packing graded poultry products into a shipping case.

It is another object of this invention to provide a working table designed for expediting the labeling and packaging of poultry products.

It is another object of this invention to provide a working table to be used for the lining of a shipping case, the labeling of poultry product, and the loading of the labeled product into the lined box.

It is another object of this invention to provide a working table for accommodating different sizes of shipping cases which are adapted to receive different grades of poultry product while the respective boxes are being loaded.

It is another object of this invention to provide a working table for the accommodation of different sizes of shipping cases and different sizes of paper liner material to be used in the lining of the box.

It is another object of this invention to provide a working table wherein different sizes of paper liner material may be measured off for the lining of different sizes of boxes which are to be loaded.

Other objects will appear from the specification below.

In the drawings:

Figure 1 is a front elevation of a preferred embodiment of this invention;

Figure 2 is a side elevation of the packing table; and

Figure 3 is a top plan view of the packing table.

The present invention has been made particularly for use with the grading bin structure shown in my copending application entitled, "Poultry Grading Bin," Serial No. 42,213, filed August 3, 1948, now Patent No. 2,582,641. This packing bench, as well as the grading bin structure, are both provided for use in the modern poultry packing plant which is designed to handle a large volume of product, and the present invention func-

2

tions at the grading and packing station to materially speed up the ultimate packing of the dressed product for shipment into retail channels.

5 Poultry from the dressing line is graded into a number of different classifications as described in my above-mentioned application. Ordinarily, during any particular season the entire production of the poultry product is graded into as many as 27 different classifications, depending upon the characteristics of color, weight, body structure, and the like. After the product has been graded it is placed in a proper bin along with other product of the same grade. The product 10 remains stored in these grading bins while wash water drains from the dressed poultry, and as the individual bins become filled, they are removed from the grading rack and are delivered to the packing table of this invention. At this station 15 the birds are removed from their respective grading bins and are packed into wire-bound boxes of just the right size to suitably accommodate 12 of the dressed poultry carcasses.

In the usual packaging of such product for 20 shipment into the retail trade, the packing box is lined with paper on all sides and at the ends, and the birds are packed into the box in a manner to have a snug fit. The birds are preferably labeled at this stage of the packaging procedure with a decal, which is stuck onto the breast of each carcass. When 12 carcasses have been placed in a box, the liner material is folded over the product and the box is closed.

The packing table of this invention provides an 25 improved arrangement for fixedly holding the wire-bound boxes while they are being lined with paper and loaded. A suitable clamping means is built into the table to hold the box, and the box is tipped up somewhat to provide a convenient angle for working in it so that the individual carcasses may be snugly fitted into the container. The table also has a means for holding the grading bin into which the dressed carcasses have been loaded, so that the individual carcasses may be 30 conveniently handled while being passed from the grading bin to the wire-bound box. A labeling station is situated between the grading-bin holder and the box holder so that each carcass may be labeled before it is positioned in the box being loaded. The packing table also includes a suitable storage means adjacent the box-loading position for holding several rolls of paper liner material in such a manner that it may be measured off and placed in the box.

35 Referring to the preferred form of the inven-

tion, shown in the drawings, the table structure is mounted on suitable supports 10, and at the right side of the table, as best shown in Figure 1, a box holder 11 is provided to accommodate wire-bound boxes of different sizes. At holder 11, a pair of supporting bars 12 and 13 are carried in the frame of the table, and a clamping plate 14 is movably mounted on bars 12 and 13 so as to slide laterally whereby to clamp the box to be loaded between it and the fixed wall 15 integral with the table. The clamping plate 14 may be mounted from suitable slide-bearing guides 16 and 17 which ride on the supporting bars 12 and 13, so that the plate 14 is always held parallel with the wall 15, and a suitable ratchet means is provided for holding plate 14 tight against a box positioned between the clamp plate 14 and plate 15. The ratchet includes a detent 20 and a ratchet 21, which cooperate to hold the clamp plate 14 fixed against the wall of a box. The detent may be released after a box has been loaded by lifting the handle 22 fixed to the detent.

A plurality of rolls of paper for lining the box is carried above the box-holding station, and these rolls are carried in a frame 25, fixedly supported from the table. The rolls are positioned such that the several rolls of paper 26, 27, and 28 are held approximately over a box to be loaded, which has been clamped between the clamping plate 14 and fixed plate 15 and is held on bars 12 and 13. The rolls of paper are cut to have different widths and each roll provides lining material to be used in the packing of a box of particular size. Each of the rolls of paper is double rolled; i. e., two sheets of paper are simultaneously wrapped together to form the paper rolls, and the rolls are mounted in frame 25 with the rolls 26 and 27 of shorter width disposed toward the back end of the table and with the longer roll 28 hung from the front side of frame 25 in somewhat overlapping relationship with respect to roll 27. Each of the rolls has a cut-off bar 29 mounted across the front face thereof, and fixed to each of the cut-off bars is a measuring ruler 30. Each of the rulers 30 is marked off in units equivalent to the grade of poultry being packed for a purpose that will appear more fully below.

To the left of the box-holding station a suitable grading bin support rack 40 is provided for holding the respective grading bins while poultry product is being transferred to the particular lined box being filled. The bin-holding station 40 is provided with suitable drain openings 41 which cooperate with the drain openings in the bins so that washwater and the like may continue to drain from the grading bins, and preferably the grading bins are held at a slight angle so that such drainage is encouraged.

Between the box-holding station and the bin-holding means, a suitable label supply is situated which includes several pockets 50, 51, and 52 for holding different labeling indicia. A compartment 53 is also provided for holding a suitable moistening sponge so that the decals or labels held in the different pockets may be wetted as they are about to be placed on the breasts of the poultry product being packed.

In using this packing table, a bin loaded with the graded poultry product is placed on the bin-holding means. Having a knowledge of the grade of poultry in the bin, the loader can then select a wire-bound box of proper size to snugly hold 12 of the particular poultry carcasses.

When the proper size of box has been selected,

it is placed on the bars 12 and 13 between the plates 14 and 15, and the clamping plate is moved toward the fixed plate 15 to fixedly engage the box at the box-loading station. The ratchet ordinarily falls into place and holds the clamp plate 14 tight against the box, and the box is thus held in a tilted position, facing up toward the operator.

After the box has been clamped in place, a suitable length of the double-rolled lining paper is drawn from the proper roll and measured off in accordance with the grade of poultry being packed. The measurement may be made from the grade indications provided on the measuring sticks 30, and when a proper length has been drawn off, it is served from the roll by tearing it across the cut-off bar 29. The two sheets of paper which are thus simultaneously cut off are folded in conventional manner and placed in the box to line the bottom and two sides lengthwise of the box. Then a second and shorter length of paper is drawn off from the double rolled supply so that the ends of the box may be covered with the paper liner.

After all the walls of the box have been lined as described, the poultry carcasses may be removed from the grading bin and labelled with a suitable indication of grade, trade-mark, or whatever desired labeling is to be used. As each carcass is labelled, it is placed in the lined box until 12 have been placed therein. After the carcasses have been snugly fitted into place, the side liners are folded over the top of the carcasses and then the end liners are folded into place. The wire-bound box is then closed, and after the packing operation has been completed, the detent 20 of the ratchet may be released so that the loaded box can be removed from the packing table.

The packing table here described may be used to greatly speed up the loading of graded poultry product into the conventional retail shipping case, and also provides for a much neater package in that the shipping case is held firmly in place while loading is accomplished. Also, the poultry product may be labeled and quickly loaded into the lined shipping container under the most sanitary conditions, and a compact arrangement for all labeling supplies, including the liner material, is provided. A most compact arrangement of liner material is provided in the particular mounting of the rolls of paper in frame 25 so that all of the packing material is positioned in the most convenient position for facilitating the packaging operation.

The above description covers the preferred arrangement of this invention. It is obvious that many modifications may occur to those skilled in the art, which will fall within the scope of the following claims.

I claim:

1. In a device for use in the packing of poultry into suitable shipping containers from the bins into which the poultry is placed during the grading and washing operation, wherein a table member is so positioned and arranged as to support at one end and partly depressed within the surface thereof a forwardly-inclined poultry bin, and at the other end thereof means to fixedly secure in a forwardly-inclined relationship with said table a poultry shipping container, the combination with said table of a paper holding means vertically disposed adjacent to and rearwardly of said inclined holding means for said shipping container, said paper holding means comprising

a relatively narrow vertical frame affixed to the rear of said table, a plurality of double-wound rolls of paper rotatably suspended within said frame, the lowermost rolls being suspended parallel to and substantially directly above the rear edge of said table, and the uppermost roll being suspended forwardly of said lower rolls and substantially directly above the rear edge of said container holding means to facilitate the deposition of paper from said roll within a container secured thereon, cut-off bars positioned laterally across each of said rolls and supported by said frame, and indicator means for each roll affixed to said cut-off bars and provided with indicia selected in accordance with the grade of poultry to be packed in the shipping container.

2. In a device for use in the packing of poultry into suitable shipping containers from the bins into which the poultry is placed during the grading and washing operation, wherein a table member is so positioned and arranged as to support at one end and partly depressed within the surface thereof a forwardly-inclined poultry bin, and at the other end thereof means for holding a plurality of paper rolls disposed vertically above said table, the combination with said table of a container holding means affixed to said table adjacent to and forwardly of said paper holding means, said container holding means comprising a pair of laterally extending supporting

15

20

30

bars fixedly secured to said table, the rearmost bar being at a substantially higher elevation than the foremost bar, ratchet means fixedly secured to said table member at a point to one side of and substantially midway of said bars, a pair of vertically extending clamping plates extending transversely of said bars, one of said plates being fixedly secured to said table member and the other of said plates being movably mounted on guide means adapted to slide along said bars, detent means affixed to said movably mounted plate and adapted to engage said ratchet means, and means to release the detent from engagement with said ratchet.
